REAMER

John A. Zublin, Los Angeles, Calif.

Application August 29, 1938, Serial No. 227,278

14 Claims. (Cl. 255—73.)

This invention relates to rotary drilling tools for producing bore holes in the earth, and more particularly to a reamer having roller cutters mounted thereon.

5 It is an object of this invention to provide a reamer having roller cutters that are easily assembled to a supporting shank and disassembled therefrom.

A further object of the invention is concerned 10 with a reamer having roller cutter assemblies that can be attached to their supporting shank at various distances from the center line of the reamer, thereby making it possible to use the same sizes of parts for producing different bore 15 hole diameters.

Still another object of the invention is to attach cutters to a supporting body by suitable means and to prevent loss of the cutters in the event of failure of the particular means used.

20 It is preferred that the attaching means be welded material.

This invention possesses many other advantages and has other objects that will become apparent from a consideration of an embodiment 25 of the invention. For this purpose, a form is shown in the drawing accompanying and forming part of the present specification, which embodiment will now be described in detail, illustrating the general principles of the invention.

30 However, it is to be understood that this detailed description is not to be taken in a limited sense, since the scope of the invention is best defined by the appended claims.

Referring to the drawing:

35 Figure 1 is a side elevation of a reamer embodying the invention, parts being shown in section.

Figure 2 is an elevation of a reamer as seen from the right of Figure 1.

40 Figure 3 is a transverse section taken along the plane 3—3 of Figure 1.

Figure 4 is a transverse section taken along the line 4—4 of Figure 1.

The reamer disclosed includes a supporting 45 body or shank 10 having a tapered threaded pin 11 at one end and suitable means, as a threaded box 12, at the other end whereby the reamer can be attached to another rotary cutting tool or any other desired mechanism (not shown). The

50 reamer includes a pair of circumferentially adjacent roller cutter assemblies 13, 13 on one side and a single roller cutter assembly 14 substantially diametrically opposite the central plane of the first-mentioned pair of cutters. This arrangement forms the subject matter of my ap-

plication Serial No. 218,491, filed July 11, 1938. Two coaxial cutters 13a, 13b and 14a, 14b are shown as being in each set, these cutters being rotatably mounted upon a bearing pin 15 secured to the shank 10 in the manner to be described hereinafter. However, it is to be understood that although two coaxial rollers are mounted on each pin, a single roller or more than two rollers can be used without departing from the scope of the invention.

The rollers are received by the shank within recesses or grooves 16, the ends of which terminate in notches 17 adapted to receive the ends 15a of the roller bearing pins 15.

The shank is provided with a passageway 18 for drilling fluid which can pass through nozzles 19 communicating with the passageway 18 and the recesses or grooves 16 to direct a jet of drilling fluid upon the cutter teeth to clean them of adhering matter and assist their rotation on their bearing pins 15; all of which is described and claimed in my co-pending applications Serial No. 218,491, filed July 11, 1938, and Serial No. 191,621, filed February 21, 1938.

The roller cutters and their bearing pins are 25 so mounted on and supported by the shank as to be easily assembled thereto and disassembled therefrom. In furtherance of this end, flat, generally rectangular plates 20, 20 are provided near the respective ends of the adjacent sets of coaxial rollers 13, these plates being affixed to the adjacent portions of the bearing pins 15. The pins 15 pass through bores 21 formed in respective plates and are rigidly secured thereto by welding in the material 22 between the outer 30 surfaces of the pins and the inner surface of the bores 23 in the plates. To properly center the pins in the plates, the bore diameter 23a adjacent the ends of the cutters is only slightly 35 larger than the diameter of the pins in order to 40 snugly fit therearound. The remainder of each plate bore 23b is enlarged to receive the welded material aforementioned.

Considering the right sets of rollers 13, as seen 45 in Figures 1 and 3, they are assembled with respect to the plates 20 and pins 15 by placing each pin through one plate and through the rollers, after which the pin will pass through the other plate. The welding material 22 is then fused into the enlarged bore plate portions. A 50 similar procedure is adopted regarding the single set of rollers 14a, 14b shown at the left of Figures 1 and 3. However, the plates 24 for these rollers are preferably generally triangular in 55 shape to provide a greater surface for their at-

tachment to the shank, and also so that they will conform to the outer surface of the shank in the region of this set of rollers 14a, 14b.

After the pins 15 are welded to the plates 20 or 24, each assembly 13 or 14 can be inserted into the grooves or recesses 16 with the ends 15a of the pins 15 confined by the notches 17 in the shank. The plates 20 or 24 are then integrated to the shank by welding in the fillets 25 between the sides of the plates and the ends of the grooves. By reason of this welded in material 25, each entire assembly is securely attached to the shank 10. Whenever the cutters are worn and require replacement the welded fillets 25 can be burned away by use of a suitable cutting torch, or other means, and the assembly removed from the shank without any material damage thereto.

It will be noted that the ends 15a of the pins 20 are not welded to the shank, but that the sole means of attachment between the shank and the cutter assemblies 13 or 14 is through the plates 20 or 24. This has a decided advantage over a construction in which the ends of the pins 25 themselves are welded to the shank because of the ease with which the cutter parts can be removed. There is a further advantage in that there is no necessity for accurate finishing of the notches 17 or of precision drilling or reaming of aligned holes (not shown) to receive the ends of the pins. The notches can be cast sufficiently accurately to confine the ends of the pins and be positioned closely adjacent to them. They serve as a safety factor by preventing loss of 35 the cutters and other parts in the hole in the event that the welded fillets 25 become fractured. The sides of the notches will prevent movement of the pins laterally in at least three directions while the walls of the bore being drilled will prevent the cutter assembly from moving substantially radially outward in the event that the welds fail.

Due to the use of the plates, the same diameter of cutters and pins can be used for reaming a 45 variety of bore hole sizes. This will become apparent when it is realized that the assembly can be moved into the notches 17 and grooves 16 at varying distances from the center line of the bit, and the fillets 25 thereafter welded in place. 50 However, for rapidity in making the assembly, at a consequent saving in the cost of manufacture, the bottom portions 16a of the grooves 16 are preferably finished to engage a side surface 20a or 24a of each plate. This arrangement will 55 relieve the welds 25 of substantially all strain since the loads encountered by the cutters will be transmitted from them through the pins and plates directly to the shank through the abutting shank and plate surfaces. With this arrangement the same size cutters can still be used for reaming different size bore holes merely by the use of plates of different widths which will position the center line of the bearing pins differently with respect to the finished shank surfaces.

65 I claim:

1. A reamer including a shank provided with a circumferential groove, roller cutter means within said groove, a bearing pin on which said cutter means is mounted, a plurality of plates to which 70 said pin is fixed, and means for attaching said plates to said shank.
2. A reamer including a shank provided with a circumferential groove, roller cutter means within said groove, a bearing pin on which said cutter 75 means is mounted, a plurality of plates to which

said pin is fixed, said plates having bores through which said pin extends and in which it is welded to said plates, and means for attaching said plates to said shank.

3. A reamer including a shank provided with a circumferential groove, roller cutter means within said groove, a bearing pin on which said cutter means is mounted, a plate at each end of the cutter means, the ends of said pin extending into and welded to respective plates, and said plates welded 10 to said shank.

4. A reamer including a shank provided with a circumferential groove and notches at the ends of said groove, roller cutter means within said groove, a bearing pin on which said cutter means is mounted, a plate at each end of the cutter means, the ends of said pin extending through 15 respective plates into respective notches, said pin being welded to said plates, and said plates being welded to said shank.

5. A reamer including a shank provided with a circumferential groove having bottom and end walls, notches in said shank adjacent said end walls, roller cutter means within said groove, a bearing pin on which said cutter means is mounted, a plate at each end of the cutter means, the ends of said pin extending through 25 respective plates into respective notches, said pin being welded to said plates, and said plates engaging said bottom wall and welded to said end walls.

6. A reamer including a shank provided with a circumferential groove having bottom and end walls, notches in said shank adjacent said end walls, roller cutter means within said groove, a bearing pin on which said cutter means is mounted, a plate at each end of the cutter means, the ends of said pin extending through 30 respective plates into respective notches, said plates having respective enlarged bores in which said pin is welded to each plate, and said plates engaging 35 said bottom wall and welded to said end walls.

7. A reamer including a shank provided with a circumferential groove having bottom and end walls, said groove being open at its side portions between said end walls, said shank having outwardly opening notches adjacent said end walls, roller cutter means within said groove, a bearing pin on which said cutter means is mounted, a plate at each end of the cutter means, the ends of said pin being secured to said plates and 45 extending therethrough into respective notches, said plates being welded to said end walls near the open side portions of the groove.

8. A reamer including a unitary shank provided with a circumferential groove having bottom and 50 end walls and also an outwardly opening notch adjacent each end wall, said shank being open at the side portions of the groove between the end walls, roller cutter means within said groove, a bearing pin on which said cutter means is 55 mounted, a plate at each end of the cutter means, the ends of said pin being secured to said plates and extending therethrough into respective notches, said plates engaging said bottom wall and welded to said end walls near the open side 60 portions of the groove.

9. A reamer including a shank provided with a circumferential groove having bottom and end walls, said groove being open at its side portions between said end walls, said shank having a plurality of outwardly opening notches adjacent each 70 end wall, bearing pins having end portions within said notches, a plate adjacent each end wall through which said pins extend and to which they are secured, said plates being welded to said 75

end walls near the open side portions of the groove, and roller cutter means mounted on each bearing pin.

5 10. A reamer including a shank provided with a circumferential groove having bottom and end walls, said groove being open at its side portions between said end walls, said shank having a pair of circumferentially adjacent outwardly opening notches adjacent each end wall, a pair of bearing pins having end portions within said notches, roller cutter means on each pin, a plate at each end of the cutter means through which said pins extend and to which they are secured, said plates being welded to said end walls.

15 11. A reamer cutter assembly comprising a pair of plates each having a bore therethrough, a bearing pin in said bores extending through and projecting beyond said plates, said pin being secured to said plates by welding material in said bores circumferentially around said pin, and roller cutter means mounted on said pin between said plates.

20 12. A reamer cutter assembly comprising a pair of plates each having a bore therethrough, a

bearing pin in said bores extending through and projecting beyond said plates, each bore having a diameter to center the pin in the plates and an enlarged diameter to form a circumferential recess to receive welding material for securing the pin to the plates, and roller cutter means mounted on said pin between said plates.

13. A reamer cutter assembly comprising an upper plate and a lower plate, a pair of bores in said upper plate; a pair of bores in said lower plate in alignment with the bores in said upper plate, bearing pins extending into aligned bores in said plates, each bore having a diameter to center the pins in the plates and an enlarged diameter to form a circumferential recess to receive welding material for securing the pins to the plates, and roller cutter means mounted on each pin between said plates.

14. A reamer cutter assembly comprising a pair of plates, a bearing pin fixed to each plate with its ends projecting therebeyond, and roller cutter means mounted on said pin between said plates.
